ENCLOSED CARROUSEL TOY

Willis M. Lakin, Barton, Wis., assignor to Marlin Toy
Products, Inc., Horicon, Wis., a corporation of Illinois

Filed Oct. 1, 1964, Ser. No. 81,963

Term of patent 14 years

(Cl. D34—15)

Fig. 1.

Fig. 2.

Fig. 3.

Fig. 4.

The side opposite that seen in FIGURE 1 is substantially the same as that shown.

I claim:

The ornamental design for an enclosed carrousel toy, as shown and described.
